Armstrong Teasdale LLP(57) CLAIM

I claim the ornamental design for a football-shaped container, as shown and described.

DESCRIPTION

FIG. 1 is a perspective view of an assembled football-shaped container.

FIG. 2 is a perspective view of a top portion of the football-shaped container in FIG. 1; and,

FIG. 3 is a perspective view of a bottom portion of the football-shaped container shown in FIG. 1.

The broken line showing of environment in the drawings is included for the purpose of illustrating only and forms no part of the claimed design.
